Primary Examiner — Bridget L Eland(74) *Attorney, Agent, or Firm* — Mark Terry(57) **CLAIM**

The ornamental design for a housing for electrical equipment, as shown and described.

DESCRIPTION

FIG. 1 is a top perspective view of the housing for electrical equipment, showing the new design;

FIG. 2 is a bottom perspective view thereof;

FIG. 3 is a front view thereof;

FIG. 4 is a top view thereof;

FIG. 5 is a bottom view thereof;

FIG. 6 is a rear view thereof;

FIG. 7 is right side view thereof; and,

FIG. 8 is a left side view thereof.

(Continued)

The uniformly dashed lines shown in the drawings illustrate portions of the housing for electrical equipment which form no part of the claimed design.
